UNITED STATES PATENT OFFICE.

ELLSWORTH A. HAWTHORNE, OF BRIDGEPORT, CONNECTICUT.

LAMP.

1,242,185.

Specification of Letters Patent.

Patented Oct. 9, 1917.

Application filed May 8, 1917. Serial No. 167,183.

To all whom it may concern:

Be it known that I, ELLSWORTH A. HAWTHORNE, a citizen of the United States, and a resident of Bridgeport, in the county of 5 Fairfield and State of Connecticut, have invented an Improvement in Lamps, of which the following description, in connection with the accompanying drawings, is a specification, like characters on the drawings representing like parts.

This invention relates to lamps, and is more particularly concerned with means for facilitating the assembling and the fastening together of the lamp casing, its glazing and its reflector.

My invention will be best understood by reference to the following description when taken in connection with the accompanying drawings of one specific embodiment there- 20 of, while its scope will be more particularly pointed out in the appended claims.

In the drawings:

Figure 1 is a central, longitudinal, sectional, view of a lamp embodying my in- 25 vention;

Fig. 2 is a detail, central, longitudinal, sectional view of some of the parts shown in Fig. 1, illustrating the mode of as- 30 sembling;

Fig. 3 is a detail view showing in elevation a portion of the body of the lamp casing, and showing in section one of the screws constituting a part of the clamping means;

Fig. 4 is a sectional view on line 4—4 of 35 Fig. 1; and

Fig. 5 and 6 are detail views of one of the retaining elements or clamps.

Referring to the drawings, and to the embodiment of my invention which I have 40 selected for illustration, I have there shown a lamp comprising a suitable light source 7, associated with an appropriate reflector 8 and both mounted within a casing comprising a body 9 and a bezel or door 10, the 45 latter being provided with a seat 11 for a suitable glazing or light-transmitting element 12.

As a means for insuring the exclusion of dust, water, and other foreign substances, 50 the door or bezel 10 is herein provided with an annular recess 13 containing a ring of suitable packing material 14, such for example as a strip of felt, which before being put in place may be coated on both sides 55 with some suitable substance such as shellac which will adhere to the abutting surfaces

and contribute to produce a tight joint. As a further means to insure a tight joint between the glazing and door or bezel, the seat 11 may be, and is herein, disposed at a slight acute angle to the face of the glazing, and is made resilient so that when sufficient pressure is exerted against the inner side of the glazing, the seat will be tensioned and a snug fit against the face of the glazing secured. The reflector 8 may be otherwise suitably mounted within the casing, but herein is provided with a flange 15 disposed flatwise against the inner face of the glazing, and may be and preferably is held 70 in firm engagement therewith by the same means hereinafter described, which holds the glazing against its seat.

I have herein provided a single means to secure the casing parts together to hold the 75 glazing against its seat, and to retain the reflector in its place, the arrangement being such that by the use of a screw or screws accessible from the exterior of the casing, such means is rendered effective to exert 80 axial thrusts against the casing parts and against the glazing and reflector to urge them into their respective places.

This means may take many forms within the spirit and scope of the appended claims, 85 but herein comprises a plurality of screws 16 and coöperating nuts 17 of any suitable number, preferably spaced at equal intervals around the lamp casing, said screws extending from the exterior to the interior of the 90 latter, and said nuts being disposed within the casing. Preferably, also, the screws are disposed radially with relation to the common axis A—A of the casing parts 9 and 10, which it will be observed are telescopically 95 arranged with relation to each other, the part 9 to this end being provided with a generally cylindrical flange 18, and the part 10 being provided with an encircling, generally cylindrical flange 19, one of which has 100 a snug working fit over the other.

As a means to limit the inward movement of the flange 19 with relation to the flange 18, and to provide a tight dust and moisture excluding joint for the two casing parts, the 105 part 9 is herein provided with a seat 20 in the form of a circumferential bead, and the part 10 is provided with a circumferential bead 21 which fits thereagainst when the lamp is fully assembled. The cylindrical 110 flange 18 of the casing body 9 is herein provided with a plurality of openings 22 cor-

responding in number to the screws 16 to receive the latter. These openings may be of any appropriate character, but herein each has a generally V-shaped notch 23 merging into a laterally widened mouth or entrance 24. This is a feature of considerable practical importance in the assembling of the lamp, since the flange 18 of the part 9 can be introduced into the flange 19 of the part 10, then turned until the screws 16 enter the widened entrance 24, and then again turned until the screws enter the V-shaped notches 23. It is found in practice that this can be done very expeditiously with only a most casual inspection of the parts before commencing the assembling. It should here be observed that the screws 16, even when in the positions which they finally occupy, are separated from the bottoms of their respective notches 23 by a sufficient space, so that there is no danger whatever of their interfering with the bead 21 being brought snugly against the bead 20.

As a means for translating the turning movement of the screws 16 into axial movement of the casing parts 9 and 10, I have herein provided means carried by the nut 17 to enforce rectilinear movement of the latter in a radial direction, and to utilize such movement to draw the bead 21 against the bead 20. This means may take other forms, but herein the nut 17 is provided with an arm or lug 25, which is inclined or oblique to the axis of the screw 16, and constitutes a wedge which coöperates with a suitably formed shoulder 26 in the casing body 9. This shoulder may be of other suitable character, but herein is rounded and inclined as clearly illustrated in Figs. 1 and 2 for coöperation with the inclined wedge 25, and for convenience in manufacture is formed as a part of an annular groove 27 within the bead 20. It should be apparent that by turning each of the screws 16 in the proper direction, each of the nuts 17 will be caused to move radially outward, and to approach the flange 18. This produces a wedging action of the inclined arm 25 on the inclined shoulder 26, the result being that the two casing parts are moved axially with relation one to the other, and the beads 20 and 21 are forcibly crowded against each other in such a manner as to produce a tight joint which will exclude dust, water and other foreign substances.

Similar means are provided for forcing the reflector flange 15 against the glazing 12, and in turn forcing the latter against its seat 11. To this end, the nut 17 carries one or more, herein a plurality of arms 28, preferably formed integral with said nut and disposed obliquely, or inclined oppositely to the arm 25, thus constituting wedging means coöperating with a suitable shoulder 29 formed on the flange 19 of the part 10.

This shoulder may be otherwise suitably formed, but herein is formed as a part of an annular groove 30 within a bead 31. It should here be noted, incidentally, that the wedging action of the arms 28 against the shoulder 29 naturally contributes in forcing the beads 20 and 21 together. The arms 28 are arranged to utilize the wedging action just described to urge the reflector flange 15 against the glazing 12, and in turn to urge the latter against its seat 11. To this end, the nut 17 also carries one or more, herein a plurality of arms 32 extending in a direction generally opposite to the arms 28. Herein, for convenience of manufacture, the arms 32 are, as a matter of fact, formed integral with the arms 28 respectively, although it is not at all essential. However, by making them integral, as shown, and by giving them a proper degree of flexibility, the arms are caused to urge the glazing against its seat with spring pressure. Moreover, by the provision of a plurality of flexible arms, they accommodate themselves to the surface against which they bear, and take care of any possible inequality or irregularity which might otherwise result in the strong pressure brought to bear against the glazing, causing the latter to break. These flexible arms have still another important advantage,—that of providing for possible variations in the thickness of the glazing within reasonable limits. It is very often found in practice that glazings vary a few thousandths of an inch one way or the other from a specified gage, and that sometimes even in one glazing, there will be variations in thickness from one point to another, but any such variations within reasonable limits are easily taken care of by the resilient action of the described retaining devices. It should be noted in passing that the nuts 17 and their arms 25, 28 and 32, are preferably formed on a curve corresponding with that of the casing, as it is found in practice that this shape gives the most satisfactory results.

In assembling the lamp, the packing strip 14 is first put in its place in the groove 13 in the manner previously described, and the glazing 12 placed against the packing strip and against the seat 11, it being understood, however, that the packing strip at the start will have a sufficient thickness so that it will be very considerably compressed before the glazing brings up against its seat 11. The flange 15 of the reflector 8 is next placed against the glazing, after which the screws 16 are introduced through their respective perforations in the flange 19 and loosely assembled with their respective nuts 17. The casing parts 9 and 10 are then assembled in the manner previously described by introducing the flange 18 into the flange 19 until

the screws 16 and nuts 17 occupy some such position as that illustrated in Fig. 2. It is found in practice that the arms 25 will find their way readily into the annular grooves 27, and will initially slightly interlock with the shoulder 26.

All that remains to be done is to turn the screws 16 in the proper direction to cause their respective nuts 17 to approach the flange 18, the arms 25 and 28 commence to ride down their respective inclined shoulders 26 and 29, and the casing parts 9 and 10 are drawn together with a very powerful action. By comparison of Figs. 1 and 2, it will be noted that as the arms 28 ride along the inclined surface 29, a curious flexing action takes place—firstly, the arms 28 bend close to the body portion of the nut 17; and secondly, a bending action takes place between the arms 28 and the arms 32, it being observed that the latter, though at first disposed somewhat at an angle to the flange 15, are bent and tensioned until they finally occupy some such position as that illustrated in Fig. 1, substantially flatwise against said flange. By this time, the rounded bends of the resilient arms have reached a position where they seat at or near the bottom of the annular groove 30. The flange 15 is now held with firm, though somewhat resilient, pressure against the glazing 12, and the latter against its seat 11, and the seat in turn is tensioned so that it also contributes in producing a tight dust and moisture excluding joint, yet without danger of breakage of the glazing. One of the distinct advantages of the described construction is that it provides an exceedingly simple assembly, which is easily understood, not only by comparatively unskilled factory workers, but also by the general purchasing public into whose hands the lamp goes. The parts can be readily dismounted by simply reversing the foregoing operation, and re-assembled with ease by the aid of a screw-driver. This is, of course, a distinct advantage in the case of the breakage of a glazing in the event of a collision.

While I have herein shown and described one form or embodiment of my invention for illustrative purposes, and have disclosed and discussed in detail the construction and arrangement incidental to one specific application thereof, it is to be understood that the invention is limited neither to the mere details or relative arrangement of parts, nor to the specific embodiment herein shown, but that extensive deviations from the illustrated form or embodiment of the invention may be made without departing from the principles thereof.

Having thus described my invention, what I claim and desire by Letters Patent to secure is:

65 1. In combination, a glazing, a casing hav-

ing a seat for said glazing, and means for holding said glazing against said seat including a clamping member having an integral resilient portion, and means to tension said resilient portion to cause the same to urge said glazing against said seat.

2. In combination, a glazing, a casing having a seat for said glazing, and means for holding said glazing against said seat including a clamping member having a plurality of resilient fingers, and means to tension said fingers to cause the same to urge said glazing against said seat.

3. In combination, a glazing, a casing having a seat for said glazing, and means for holding said glazing against said seat, including a clamp interlocking with said casing, and a screw to cause said clamp to hold said glazing against said seat and to hold said clamp in interlocking engagement with said casing.

4. In combination, a glazing, a casing having a seat for said glazing, and means for holding said glazing against said seat, including a clamp interlocking with said casing and having a resilient portion, and a screw to tension said resilient portion to urge said glazing against said seat and to hold said clamp in interlocking engagement with said casing.

5. In combination, a glazing, a casing having a seat for said glazing, and means for holding said glazing against said seat, including a clamp having a part projecting in one direction into interlocking engagement with said casing and another part projecting in a generally opposite direction, and a screw to hold the one part in such interlocking engagement and to cause the other part to hold said glazing against said seat.

6. In combination, a glazing, a casing having a seat for said glazing, and means for holding said glazing against said seat, including a clamp having a part projecting in one direction into interlocking engagement with said casing and a resilient part projecting in a generally opposite direction, and a screw to hold the one part in such interlocking engagement and to tension said resilient portion and to cause the latter to urge said glazing against said seat.

7. In combination, a glazing, a casing having a seat for said glazing and having a shoulder adjacent the margin of said glazing, and means for holding said glazing against said seat, including a retaining member engaging said shoulder, and means to cause said member to co-operate with said shoulder and to react on said glazing to urge the latter against said seat.

8. In combination, a glazing, a casing having a seat for said glazing and having an inclined shoulder adjacent the margin of said casing, and means for holding said

- glazing against said seat, including a retaining member engaging said inclined shoulder, and means to cause said member to coöperate with the incline of said shoulder 5 and to react on said glazing to urge the latter against said seat.
9. In combination, a glazing, a casing having a seat for said glazing and having an annular shoulder adjacent the margin of 10 said glazing, and means for holding said glazing against said seat, including a retaining member engaging said shoulder, and means to cause said member to coöperate with said shoulder and to react on said 15 glazing to urge the latter against said seat.
10. In combination, a glazing, a casing having a seat for said glazing and having an annular inclined shoulder adjacent the margin of said casing, and means for holding 20 said glazing against said seat, including a retaining member engaging said inclined shoulder, and means to cause said member to coöperate with the incline of said shoulder and to react on said glazing to urge the latter 25 against said seat.
11. In combination, a casing comprising two telescopically arranged parts one of which has a seat against which the other is seated by axial movement, and means for 30 relatively moving said parts to cause such seating, said means including a radially disposed screw and means to translate turning movement of said screw into axial movement of said parts.
12. In combination, a casing comprising two telescopically arranged parts one of which has a seat against which the other is seated by axial movement, and means for 35 relatively moving said parts to cause such seating, said means including a radially disposed screw and means having a wedging action to translate turning movement of said screw into axial movement of said parts.
13. In combination, a casing comprising two telescopically arranged parts one of which has a seat against which the other is seated by axial movement, and means for 45 relatively moving said parts to cause such seating, said means including a radially disposed screw and means having a plurality of inclined sliding wedge-like surfaces to translate turning movement of said screw into axial movement of said parts.
14. In combination, a casing comprising 55 two telescopically arranged parts one of which has a seat against which the other is seated by axial movement, and means for relatively moving said parts to cause such seating, said means including a radially disposed screw, a device connected with said screw, means to translate turning movement of said screw into rectilinear movement of said device, and means to translate said rectilinear movement into axial movement of 60 said parts.
15. In combination, a casing comprising two telescopically arranged parts one of which has a seat against which the other is seated by axial movement, and means for relatively moving said parts to cause such seating, said means including a radially disposed screw, a nut having screw-threaded engagement with said screw, and means carried by said nut to translate rectilinear movement of said nut into axial movement of said parts. 70
16. In combination, a casing comprising two telescopically arranged parts one of which has a seat against which the other is seated by axial movement, and means for relatively moving said parts to cause such seating, said means including a radially disposed screw, a nut having screw-threaded engagement with said screw, and means carried by said nut to enforce rectilinear movement thereof and to translate rectilinear movement thereof into axial movement of said parts. 75
17. In combination, a casing comprising two telescopically arranged parts one of which has a seat against which the other is seated by axial movement, and means for relatively moving said parts to cause such seating, said means including a radially disposed screw, a nut having screw-threaded engagement with said screw, and wedge means carried by said nut to enforce rectilinear movement of said nut and to translate rectilinear movement of said nut into axial movement of said parts. 80
18. In combination, a casing comprising two telescopically arranged parts one of which has a seat against which the other is seated by axial movement, and means for relatively moving said parts to cause such seating, said means including a radially disposed screw, a nut having screw-threaded engagement with said screw, and means having two pairs of inclined surfaces simultaneously acting to enforce rectilinear movement of said nut and to translate said rectilinear movement into axial movement of said parts. 85
19. In combination, a casing comprising two telescopically arranged parts one of which has a seat against which the other is seated by axial movement, and means for relatively moving said parts to cause such seating, said means including a radially disposed screw extending through said casing, and means to translate turning movement of said screw into axial movement of said parts. 90
20. In combination, a casing comprising two telescopically arranged parts one of which has a seat against which the other is seated by axial movement, and means for relatively moving said parts to cause such seating, said means including a radially disposed screw extending from the outside 125
- 65 said parts. 130

to the inside of said casing, and means within said casing to translate turning movement of said screw into axial movement of said parts.

5 21. In combination, a casing comprising two telescopically arranged parts one of which is provided with a seat against which the other is seated by axial movement, said parts being provided, respectively, with shoulders, and means for relatively moving said parts to cause such seating, said means including a radially disposed screw and means coöperating with said screw and said shoulders to translate turning movement of said screw into axial movement of said parts. 70

22. In combination, a casing comprising two telescopically arranged parts one of which is provided with a seat against which the other is seated by axial movement, said parts being provided, respectively, with shoulders, and means for relatively moving said parts to cause such seating, said means including a screw extending from the outside to the inside of said casing, and means within said casing coöperating with said screw and said shoulders to translate turning movement of said screw into axial movement of said parts. 75

23. In combination, a casing comprising two telescopically arranged parts one of which is provided with a seat against which the other is seated by axial movement, said parts being provided, respectively, with shoulders, and means for relatively moving said parts to cause such seating, said means including a radially disposed screw and wedge means operated by said screw and coöperating with said shoulders to translate turning movement of said screw into axial movement of said parts. 80

24. In combination, a casing comprising two telescopically arranged parts one of which is provided with a seat against which the other is seated by axial movement, said parts being provided, respectively, with oppositely inclined shoulders, and means for relatively moving said parts to cause such seating, said means including a radially disposed screw and means coöperating with said screw and said shoulders to translate turning movement of said screw into axial movement of said parts. 85

25. In combination, a casing comprising two telescopically arranged parts, and means for locking said parts against relative movement, said means including a screw extending from the exterior to the interior of said casing, and means within said casing operated by said screw to interlock with said casing parts. 90

26. In combination, a casing comprising two telescopically arranged parts, and means for locking said parts against relative movement, said means including a screw extend-

ing from the exterior to the interior of said casing, a nut within said casing having screw-threaded engagement with said screw, and means carried by said nut to interlock with said casing parts. 95

27. In combination, a glazing, a casing comprising two telescopically arranged parts one of which is provided with a seat for said glazing, and one of which is provided with another seat against which the other part is seated by axial movement, and means for relatively moving said parts to cause said glazing to seat on its seat and said casing parts to seat, one on the said seat of the other. 100

28. In combination, a glazing, a casing comprising two telescopically arranged parts one of which is provided with a seat for said glazing, and one of which is provided with another seat against which the other part is seated by axial movement, and means for relatively moving said parts to cause said glazing to seat on its seat and said casing parts to seat, one on the said seat of the other, said means including a screw extending from the exterior to the interior of said casing, and means within said casing operated by said screw for relatively moving said parts to cause said glazing to seat on said seat and said casing parts to seat one 105 on the seat of the other. 90

29. In combination, a glazing, a casing comprising two telescopically arranged parts one of which is provided with a seat for said glazing, and one of which is provided with another seat against which the other part is seated by axial movement, and means for relatively moving said parts to cause said glazing to seat on its seat and said casing parts to seat, one on the said seat of the other, said means including a screw extending from the exterior to the interior of said casing and means comprising wedges within said casing operated by said screw to cause said glazing to seat on said seat and said casing parts to seat one on the seat of the other. 110

30. In an apparatus of the class described, the combination of a glazing, a casing in two parts one of which is provided with a seat for said glazing, a reflector within said casing, and a single means to secure said casing parts together, to hold said glazing against said seat, and to retain said reflector in its place, said means including an actuating device accessible from the exterior of said casing. 115

31. In an apparatus of the class described, the combination of a glazing, a casing in two parts one of which is provided with a seat for said glazing, a reflector within said casing, and means to secure said casing parts together, to hold said glazing against said seat, and to retain said reflector in place, said means including a screw extending from 120

125 the exterior to the interior of said casing, and means within said casing having screw-threaded engagement with said screw, and means carried by said nut to interlock with said casing parts. 130

- the exterior to the interior of said casing and means within said casing operated by said screw to exert axial thrusts against said casing parts, said glazing and said reflector.
32. In an apparatus of the class described, the combination of a casing comprising two telescopically assembled parts and means to secure said parts together, one of said parts being provided at its circumferential terminal portion with one or more openings having edges which diverge toward the terminal circumferential edge of such part, and said means extending through such opening or openings into the interior of said casing.
33. In combination, a glazing, a resilient seat for said glazing disposed at an acute angle to the face thereof, and means including a screw for urging said glazing against said seat and tensioning the latter.
34. In combination, a glazing, a resilient seat for said glazing disposed at an acute angle to the face thereof, and means including a screw and a resilient device tensioned thereby for yieldingly urging said glazing against said seat and tensioning the latter.
35. In combination, a casing comprising two coaxially arranged parts, and means to lock said parts together, including a screw extending from the exterior to the interior of said casing, and a radially movable device actuated by said screw and interlocking with both of said parts.
36. In combination, a casing comprising two coaxially arranged parts, and means to lock said parts together, including a screw extending from the exterior to the interior of said casing and a radially movable device actuated by said screw and interlocking with both of said parts on opposite sides, respectively, of said screw.
37. In combination, a casing comprising two coaxially arranged parts, and means to lock said parts together, including a screw extending from the exterior through both of said parts and a radially movable element actuated by said screw and having laterally extending portions respectively interlocking with said parts.
38. In combination, a casing comprising two coaxially arranged parts, and a plurality of independently operable locking means to draw said parts toward each other and to lock said parts together, each of said locking means comprising an actuating element, and a radially movable element actuated thereby.
39. In combination, a casing comprising two coaxially arranged and relatively coaxially movable parts, and means to lock said parts together, including a plurality of screws spaced about said casing, and a plurality of radially movable devices actuated by said screws, respectively, and interengaging with said parts.
40. In a lamp casing, the combination of a body and a closure therefor, the latter comprising a glazing and door having a resilient seat for said glazing, said seat being disposed approximately flatwise though at a slight acute angle to the contacting face of said glazing, and means to force said glazing against said seat thereby to tension the latter and reduce such angle.
41. In a lamp casing, the combination of a body and a closure therefor, the latter comprising a glazing and door having a resilient seat for said glazing, said seat being disposed approximately flatwise though at a slight acute angle to the contacting face of said glazing, and means including a screw to force said glazing against said seat thereby to tension the latter and reduce such angle.
42. In a lamp casing, the combination of a body and a closure therefor, the latter comprising a glazing and door having a resilient seat for said glazing, said seat being disposed approximately flatwise though at a slight acute angle to the contacting face of said glazing, and means to hold said glazing against said seat and to maintain the latter under tension.
- In testimony whereof, I have signed my name to this specification.

ELLSWORTH A. HAWTHORNE.
